UNITED STATES PATENT OFFICE.

STEPHEN BATTNER, OF BROOKLYN, NEW YORK.

PNEUMATIC-ACTION UNIT.

1,401,857.

Specification of Letters Patent. Patented Dec. 27, 1921.

Application filed January 9, 1920. Serial No. 350,431.

To all whom it may concern:

Be it known that I, STEPHEN BATTNER, a citizen of the United States, and a resident of the city of New York, borough of Brooklyn, in the county of Kings and State of New York, have invented a new and Improved Pneumatic-Action Unit, of which the following is a full, clear, and exact description.

10 This invention relates to pneumatic actions such as are commonly employed in connection with player pianos, organs, or other instruments or mechanisms, and has particular reference to the simplification of 15 construction which tends immediately toward economy of material and labor and increases the efficiency of the devices.

Among the objects of the invention is to 20 improve the facilities for utilizing independently manipulated pneumatic units whereby any of the units may be easily reached for inspection, repair, interchange, or the like, at any time and without disturbing any other of the units. I am aware 25 that unit structures for pneumatics have been proposed heretofore but I believe that they all are more involved and complicated, and hence liable to more structural and practical defects than my new construction.

30 With the foregoing and other objects in view the invention consists in the arrangement and combination of parts hereinafter described and claimed, and while the invention is not restricted to the exact details of construction disclosed or suggested 35 herein, still for the purpose of illustrating a practical embodiment thereof reference is had to the accompanying drawings, in which like reference characters designate 40 the same parts in the several views, and in which—

Figure 1 is a perspective view of a portion of a pneumatic action showing several of my units.

45 Fig. 2 is a vertical central section of one of my pneumatics.

Fig. 3 is a rear elevation of the inner member of the unit.

50 Fig. 4 is a rear elevation of the outer member.

Referring now more specifically to the drawings I show at 10 a tension chest which in accordance with the usual practice may be of any suitable length or cross sectional 55 design, but shown herein as having a longitudinal vacuum or tension chamber 11 ex-

tending throughout the length of the chest. This structural detail as usual is sufficiently substantial to constitute a means of support for a series of pneumatics 12 which *per se* 60 may be of any suitable construction but adapted for independent coöperation with unit valve chests or valve units 13 as they will be referred to hereinafter. The front side or face 14 of the tension chest 10 is 65 flat and smooth and is adapted to receive the several valve units 13 for independent manipulation, adjustment or control.

The vacuum chamber 11 while being substantially coextensive with the structure of 70 the chest 10 and of approximately full width of the upper portion thereof, is relatively shallow in depth. Leading forward from the vacuum chamber is a draft opening 15 in the form of a longitudinal slot and hence 75 having a large capacity for the quick movement of air impulses. Beneath the vacuum chamber and independent thereof there is formed a vent 16 direct to the atmosphere at the rear of the chest 10. This is indicated 80 as a simple cylindrical bore. Furthermore beneath the atmosphere vent 16 is formed a vent 17 leading to the pneumatic 12 directly beneath it.

Each of the valve units considered as a 85 chest comprises two main structural parts 13^a and 13^b which are of the same height and width and are adapted to mate together face to face and so be secured by any suitable means including dowel pins 18 extending 90 from one part into the other. Likewise dowels 19 may be employed between the front surface 14 of the vacuum chest and the inner members 13^b of the valve units.

The member 13^a is provided with a vacuum chamber 20^a formed in its rear side but over which is stretched loosely a diaphragm 21 having a disk 22 at its center. This diaphragm makes an air tight closure for the rear of the chamber 20^a. Communication 95 however with said chamber is had through any suitably arranged port 23 to which a tube 24 leads from a tracker board, or its equivalent, for controlling the vacuum in the chamber 20^a. A pin hole 25 or bleeder 100 port is formed at any convenient place in the member 13^a, but preferably between the rear wall thereof and the port 23.

The valve unit member 13^b is provided with a valve chamber 26 in its rear wall, said 110 chamber being in direct communication with the atmosphere and pneumatic vents 16 and

17. Supported in any suitable manner within the valve chamber 26 is a valve 27 having front and rear faces 27^a and 27^b adapted to coöperate respectively with valve seats 28^a and 28^b. The normal position however of the valve is as shown in Fig. 2 closing the port 29 and which is surrounded by said valve seat 28^a and consequently in alinement with the atmosphere vent 16. As indicated 5 10 15 20 25 30 35 40 45 50 55 60 65 70 75 80 85 90 95 100 105 110 115 120 125 130
- the valve is suspended loosely by a loose link connection 30 from the top of the valve chamber. A plurality of guides 31 are formed in the sides of the valve chamber between which the valve is adapted to play loosely, but whereby it is prevented from material lateral movement with respect to the axis of the valve. A stem 32 extends forward from the center of the valve through the port 29 in position to be struck by the disk 22 carried by the diaphragm. The front of the member 13^b is provided with a vacuum chamber 20^b constituting in effect an extension of the chamber 20^a but separated therefrom by the loosely stretched diaphragm. A draft opening 33 leads from the upper end of the vacuum chamber 20^b directly into communication with the draft opening 15 leading to the tension chamber 11.
- Any suitable means may be provided to hold the members 13^a and 13^b together or both of them as a unit to the front wall 14 of the tension chest. To this end I indicate a series of screws 34 coöperating with the tension chest between adjacent valve units 13, each screw having a plate 35 bearing against the front surface of the outer member 13^a. Thus by the loosening of any screw and the swinging of the plate carried thereby around through 90 degrees any of the valve units may be removed directly as indicated in Fig. 1.
- With a normal suction or vacuum tension in the chamber 11 the valve 27 is held seated against the seat 28^a closing the port 29. The same vacuum condition obtains in the vacuum chambers 20^a and 20^b and in the port 23 as in the tension chest 11 by reason of the equalization port or bleed hole 25. Atmospheric pressure obtains at this time in and through the port 16, valve chamber 26, port 17 and interior of the pneumatic 12. The instant however that the vacuum is broken in the port 23, as by means of the 55 60 65 70 75 80 85 90 95 100 105 110 115 120 125 130
- perforated sheet passing over the tracker board or any equivalent mechanism, which constituting no part of this invention is not shown, the suction tension acting outward from the chamber 20^b through the port 33 serves to cause the disk 22 to impinge against the valve stem 32, unseating the valve from the seat 28^a and causing the seating thereof on the seat 28^b. The interior of the pneumatic is brought consequently into direct communication with the tension chamber

through the port 17, valve chamber 26, port 29 and vacuum chamber 20^b, the stem 32 being long enough to prevent the obstruction of this communication. Therefore the pneumatic is instantly collapsed by the external pressure around it. The moment that the tension is restored in the port 23 and the pressure is equalized on opposite sides of the diaphragm the valve is restored to its normal position admitting atmospheric air again into the pneumatic. Thus it will be seen that I provide the maximum degree of simplicity and efficiency in pneumatic units insuring not only reliability of operation but durability of construction. 70 75 80 85 90 95 100 105 110 115 120 125 130

I claim:

1. In pneumatic actions, the combination of a tension chest having a smooth front face, a series of pneumatics supported by the chest and a series of valve units for the respective pneumatics, said valve units being secured independent of one another to said smooth face, each valve unit comprising two separable parts, a valve mechanism within each unit, and means serving to hold the different parts of each unit together and the unit as a whole against the tension chest. 85 90 95 100 105 110 115 120 125 130

2. In a pneumatic action, the combination of a tension chest having a vacuum space therein and an opening through one wall communicating with said space, a passage for air opening through the same wall and extending through the chest to the atmosphere, and a passage opening through the same wall and extending through the chest 95 to a point spaced from the communication with the atmosphere; a detachable sectional valve chest unit applied to the wall aforesaid and communicating with the three openings specified, said chest being provided with a valve chamber communicating with the passage to the atmosphere and with the passage last mentioned above, said unit having also a diaphragm chamber back of the valve chamber, there being a port leading from the valve chamber to the diaphragm chamber in alinement with the passage to the atmosphere, the diaphragm chamber having also a passage leading from the front portion thereof and registering with the port leading to the vacuum space of the tension chest, and the diaphragm chamber having also a passage leading therefrom through which air may be admitted from a tracker bar; a diaphragm located in the diaphragm chamber and dividing it into two parts there being a bleed port to establish communication between the two parts of the diaphragm chamber to equalize pressures on opposite sides of the diaphragm, and a pneumatic communicating with the third passage above mentioned leading through the tension chest. 110 115 120 125 130

3. In a pneumatic player-piano action, the combination of a tension chest; a detachable

- sectional valve chest unit detachably applied to one wall of the tension chest, the parts of the valve chest including a diaphragm chamber, a valve chamber and ports 5 or passages for communication with the tracker bar, the pneumatic and the atmosphere, the plane of division between the valve chest and the tension chest being so located that the wall of the tension chest 10 forms one wall of the valve chamber, and the line of division between the ports of the valve chest extending through the diaphragm chamber in a plane parallel to the face of the aforesaid wall of the tension chest; a valve in the valve chamber, and a diaphragm in the diaphragm chamber co-operating with the valve.
4. In a pneumatic player-piano action, a pneumatic, a tension chest provided with a 15 vacuum space and having an opening through one wall communicating with said space and a passage for atmospheric air extending from back to front of the tension
- chest to one side of the vacuum space, in combination with a valve chest unit applied to 25 said wall and adapted to control communications between said pneumatic and the vacuum space and air passage aforesaid.
5. In a pneumatic player-piano action, a 30 pneumatic, a tension chest having an opening through one wall communicating with the vacuum space of the chest; a passage for atmospheric air extending from back to front of the trunk to one side of the vacuum space; a passage opening through the same 35 wall and extending through the walls of the chest to a point convenient for connection with said pneumatic, in combination with a valve chest unit applied to the aforesaid wall over the openings therein and adapted 40 to control the communications between the passage connected with the pneumatic and the vacuum space and the air passage aforesaid.

STEPHEN BATTNER.
